CLAIM

The ornamental design for a watch case as shown and described.

DESCRIPTION

FIG. 1 is a top view of a watch case of my present design;
FIG. 2 is a bottom view thereof;
FIG. 3 is a right side view thereof;
FIG. 4 is a left side view thereof;
FIG. 5 is a front view thereof;
FIG. 6 is a rear view thereof; and
FIG. 7 is a top right perspective view thereof; and,
FIG. 8 is a bottom left perspective view thereof.
The broken lines depict portions of the watch case that form no part of the claimed design.

1 Claim, 8 Drawing Sheets
